UNITED STATES PATENT OFFICE.

JOHN L. PATTERSON, OF RICHMOND, VIRGINIA, ASSIGNOR TO RICHMOND BEVERAGE
MACHINE CORPORATION, OF RICHMOND, VIRGINIA, A CORPORATION OF VIRGINIA.

LIQUID-DISPENSING APPARATUS.

Application filed September 3, 1924. Serial No. 735,613.

This invention pertains to coin-controlled apparatus or machines for delivering cups or receptacles and dispensing beverages, and more particularly to such as effect the measurement and commingling of the water, gas, and syrup within the machine, and their delivery therefrom as a beverage.

The machine comprises, first, a magazine for cups, and means for delivering a single cup at a time in response to introduction of an appropriate coin or token and actuation of an operating lever; secondly, tanks or containers for water, carbonic acid gas, and a syrup or syrups; and third, means for releasing measured charges of water, gas, and syrup, and causing them to issue from a discharge nozzle upon actuation of the operating lever, and to be intimately commingled to form a carbonated beverage.

20 The invention consists in a novel construction and arrangement of parts hereinafter fully set forth, whereby the several operations are easily and accurately performed in all respects, and a cup and a filling charge 25 therefor, delivered when a coin or token of proper character is introduced and the actuating lever is depressed.

The mechanism is mounted within a casting or cabinet designed to enclose and adequately protect it, and from which the working parts may be readily removed for inspection, cleaning, repair, or replacement.

Prior to this invention numerous coin-controlled machines have been devised and 35 patented, having for their object the delivery or vending of different commodities, liquid or solid, upon the introduction of a suitable coin or token, and in some cases it has been proposed to deliver both a cup or 40 container and a liquid filling or charge therefor. In some instances, the weight of the coin, or its impact in falling, has been relied upon to actuate the mechanism, or to release a detent and permit operation by the

45 stored power of springs or the like, or the coin has been utilized to bring into action an electric motor to actuate the parts. In the practical use of prior machines it has been found difficult, owing to various causes, 50 to insure the delivery or dispensing of a drink of uniform quality or mixture, or accurately to measure and deliver a prede-

termined charge of each ingredient or component of the beverage. This invention is designed to insure accurate measurement of 55 each of the constituents of the beverage, prompt and full delivery of each, and the complete filling and emptying of the chambers in which they are measured; to eliminate leakage of the different measuring 60 chambers and sticking or binding of valves and moving parts, incident to their close fitting and packing; and to overcome other defects commonly encountered in the construction and use of such machines. 65

In the present instance I have shown and shall describe, a machine designed to give a choice of two syrups, the coin being placed in one or another slot according to the choice made. The number of syrups may 70 be increased, or a single syrup may be furnished, if desired.

My improved machine is illustrated in the accompanying drawings, in which:

Figure 1 is a front elevation of the containing case or cabinet with the front removed to show the parts within it, the cooling coils and water-measuring cylinder being indicated by dotted lines; 75

Fig. 2, a similar view at right angles to Fig. 1 but with the syrup tank and cooling chamber in section, showing the water-measuring device and the cooling coils;

Fig. 3, an enlarged sectional view of the check valve and needle valve of the dash- 85 pot whereby the timing of movement of parts is determined and controlled;

Fig. 4, a view illustrating the main actuating lever, and showing the means for insuring a full throw or complete movement 90 thereof in one direction before a reverse movement can be begun;

Fig. 5, a top plan view of the mechanism, the casing being shown in horizontal section taken in a plane just below the syrup 95 tank and ice chamber;

Fig. 6, a vertical central section through one of the syrup-measuring cylinders;

Fig. 7, a plan or face view of the metal top and bottom plates of the syrup-measuring cylinders, provided with annular V-shaped ribs which seat themselves in a packing disk to prevent leakage; 100

Fig. 8, a diagrammatic elevation of the

carbonating tanks, showing also the valve by which communication is established between the carbonator and the gas container, and between the main water tank and the atmosphere, alternately, to permit delivery of a charge of gas to the carbonator and vent the water tank to the atmosphere, under a first adjustment of the valve, and to seal the tank to the atmosphere and introduce the gas thereto, under a second adjustment;

Fig. 9, a sectional view of the distributor or four-way valve by which opposite ends of the water-measuring device are alternately connected with the water supply pipe and with the discharge nozzle;

Fig. 10, a longitudinal sectional view of the gas valve;

Fig. 11, a perspective view of the gas valve proper, in normal adjustment, the passages with which it co-acts being indicated in dotted lines as pipes or tubes;

Fig. 12, a similar view but with the valve thrown to its second position;

Fig. 13, an elevation, partly in section, of the water-measuring cylinder and its piston; and

Fig. 14, a sectional view of the four-way distributor valve, taken at right-angles to Fig. 9.

Referring first to Figs. 1, 2 and 5, it will be seen that the casing is formed of four upright or main supporting members 1 of angle iron, tied together at suitable intervals by similar but horizontally disposed angle iron bars 2, the walls 3 of sheet metal or other thin material being secured to the angle iron members by riveting or otherwise, and a door or doors being provided to give access to the mechanism. The horizontal angle irons serve to support floors or shelves 4 and 5, carrying certain portions of the mechanism as hereinafter explained, while the gas tank and carbonating cylinders may conveniently be placed in the base of the casing upon a floor similar to the shelves 4 and 5. The syrup tanks 6 and ice chamber 7 are contained within one box-like structure, but are separated one from the other by a partition 8, as seen in Fig. 2. The ice box and syrup tanks may be constructed in any approved manner, but should be formed of or lined with porcelain or block tin, to insure proper sanitary conditions.

Space is left between the syrup tanks 6 and forward of the ice chamber 7, for a stack 9 of nested paper cups, which are preferably contained within a vertical glass cylinder, resting at its lower end upon an annular metal frame 10 of a cup-delivery device of suitable form and construction. The details of this cup-delivery mechanism may vary; but a form is employed by which, upon the insertion of a coin or token of proper value

and movement of an actuating lever, the lowermost cup is released and forced off or freed from the one next above. The cup so released falls into a chute or guide 11, by which it is directed to a point beneath the discharge nozzle 12, said chute being carried by floor 5 as seen in Fig. 2. The floor 4 has in the open space between the syrup tanks 6 and forward of the ice chamber 7, an opening to allow insertion of the cup stack 9 and, if used, of its containing and guiding glass cylinder, the lower end of which latter rests upon the annular frame 10 of the cup-delivery mechanism, here shown only in general outline and without the details of the successively-acting upper and lower slides by which delivery of cups is effected. The preferred form of cup-delivery mechanism is shown and described in detail in application Serial No. 531,747, filed January 25, 1922 in the joint names of M. F. Wooten, L. R. Bivins and R. M. Nicholas, and held in the same interest as this application. It comprises upper and lower radial slides which in alternation pass beneath and withdraw from under the rolled or flanged rims of the lowermost cup and of the cup next above it, so that one is released and delivered for each oscillation forward and back of a rotary actuating cam-ring 10^a carried by the annular frame 10. The oscillation of the cam-ring is effected by either of two rollers 92 carried upon upright posts or studs 91 secured to and movable with rods 76, 77, when either rod is reciprocated, as later explained. The rollers bear against inclined faces or cams 92' carried by or movable with the actuating cam-ring 10^a, and thus impart partial rotation to the ring. Any equivalent means of actuating the cup release or delivery mechanism may be employed, and no claim is here made to such mechanism per se, but only to some form of cup delivery mechanism in combination with other mechanisms herein set forth.

It is important that the operative mechanism of the structure be readily accessible for examination, cleaning, repair, or replacement of parts, hence the main parts of such mechanism are secured to, carried by, and insertible and removable with the floor or shelf 4, which is preferably a metallic plate of suitable stiffness to sustain the weight of the mechanism without bending or sagging. To permit such insertion and removal, one flange of each angle iron corner post at the side at which such introduction and removal is to be effected, may be cut away or provided with an opening *a* in plane with and slightly wider than the thickness of the floor or plate 4, support 2 at that side being removable (see Fig. 5). Any similar construction which will permit withdrawal of the floor or shelf may be adopted.

To the under side of said plate 4 are se-

cured by bolts, screws, or other suitable fastenings, the base or framework 10 of the cup-delivery mechanism, the supports for the lever 29 and parts actuated thereby, the 5 syrup-measuring and delivery devices, the carbonated-water distributer valve 27, the mixing or delivery nozzle 12, and the pipes connecting the various parts, as hereinafter pointed out. Certain parts later described 10 are carried by certain of the parts just enumerated as being themselves carried directly by floor or shelf 4.

The gas valve 23, its actuating levers, and the dash-pot which determines the length of 15 time during which said valve moves in reversing its position, are carried by floor or shelf 5, and have no positive attachment to or connection with the mechanism carried by floor or shelf 4, hence do not interfere 20 with the removal of the latter and the parts carried by it.

The carbonating apparatus.

As indicated in Fig. 1, a carbonating apparatus is placed in the lower part of the main casing, and comprises, as shown diagrammatically in Fig. 8, a main water tank 14, and one or more smaller tanks 15, each provided with a series of foraminous dia-phragms 16, the several tanks being connected one with another in series or sequence. 25 The water tank 14 receives water at a point near its bottom by a pipe 17, communicating with an elevated reservoir or with a service main, as found convenient, said pipes being furnished with a check valve 18 seating or closing toward the source of supply, but opening under the head or pressure when the tank 14 is properly vented to the atmosphere. 30 From a point near the bottom of tank 14 a pipe 19 provided with a check valve 20 closing toward tank 14, extends to and enters the top of the nearest tank 15. Similarly, pipes 21 extend from near the bottom 35 of each tank 15 to and enter the top of the next succeeding tank 15, and finally, a pipe 22 extends from near the base of the last tank 15 to the cooling coils 26, (see Fig. 1).

A gas valve 23 serves alternately to permit gas to flow from a container (see Fig. 8), to the first carbonating tank 15 and to vent the water tank 14, and thereafter to seal the water tank 14, cut off the gas from the carbonator tanks 15, and direct it into 50 water tank 14. The venting of the water tank permits water from pipe 17 to open check valve 18 and to enter tank 14, to replace the quantity discharged from said tank into the carbonator tanks 15 and finally delivered to and discharged from the nozzle 12. The check valve 20 seats or closes toward the water tank 14, hence closes when gas pressure is on the carbonator tanks 15, and water tank 14 is vented to permit it to receive 55 water, as just stated.

The carbonator illustrated is not claimed herein *per se*, not being broadly of my invention, but it is an important element of the complete apparatus, contributes materially to its efficient operation, and will be 70 claimed in certain combinations in which it is used.

The gas valve 23 receives gas from a reservoir, container, or main by a pipe 24, and delivers it by pipe 13 to the water tank 14 75 when the latter is sealed to the atmosphere. When said tank 14 is vented by unsealing pipe 13 through the action of valve 23, the gas is delivered to that carbonator tank 15 which is next to and in immediate communication with tank 14. At such time check valve 20 between the tanks 14 and 15 is caused by the pressure of the gas in tank 15, to close toward water tank 4, which then receives water from supply pipe 17. In passing through tanks 15 both the gas and the water are broken up into a number of fine streams, and caused to commingle and produce a uniformly carbonated liquid. The pressure of the gas within the tanks serves 80 to force the carbonated water by pipe 22 to the cooling coils 26, whence it passes to the distributer valve 27 and thence to the water-measuring cylinder, as will be later explained in detail. 95

Syrup-measuring devices.

Two distinct and independent syrup-measuring and delivery devices are illustrated in 100 Fig. 5, and as they are alike in all respects, description of one will apply to both.

30 or 31 indicates the outer cylinder or shell, the upper end of which is closed by an integral head, formed with a projecting 105 flange or with ears to receive fastening bolts or screws 32 by which to secure it to the under side of floor 4. Immediately below and in close contact with the head of the cylinder is a flat disk or gasket 33 of some suitable 110 substance or material, such as cork, vegetable fiber, or the like, unaffected by and incapable of injuriously affecting the syrups used, yet sufficiently yielding to permit the embedding therein of annular V-shaped ribs 34, formed on a metallic disk 35 fitting within the cylinder 30 or 31, and pressed firmly against the disk or gasket 33. The gasket is held by a pin 36 or equivalent means, 115 against shifting or turning. The disk 35 forms the upper end or head of an internal cylinder 37, and has a series of circular openings 38 to register with circular chambers 39 formed in and extending from end to end of cylinder 37, parallel with its axis. As shown 120 in Fig. 8, the openings in disk 35 are of conical form, their lower boundaries being of the same diameter as the chambers 39, while their upper boundaries are of smaller diameter. A metallic disk 40 and gasket 41 of the 125

same form and character as disk 35 and gasket 33, and similarly held against turning, constitute the lower closure and packing of cylinder 30 or 31, the V-shaped ribs of each 5 metal disk serving to embed themselves into the contacting gasket and so to prevent entrance or passage of syrup between them, and serving further to make a liquid-tight joint of the gasket with the outer cylinder 30 or 10 31 by slightly expanding the gasket at its periphery.

Each syrup tank 6 communicates by an outlet or passage 42 with the syrup cell or chamber of cylinder 37 at the time directly 15 below it, and a like outlet 43 at the lower end of the cylinder which registers with a nipple 44, permits escape of syrup from another such cell or chamber. The inlet and outlet openings 42 and 43 are, for the purpose of showing both inlet and outlet in the one figure, here shown as on diametrically opposite sides of the cylinder axis, and as there are four chambers or cells 39 in the cylinder 37, one chamber will receive its 20 charge at the same time that another is delivering its charge, and with the inlets and outlets in 180 degree relation, an intermediate chamber would at such time be full and ready to move to the discharging position 25 and to begin its discharge simultaneously with commencement of the filling of the chamber at the same time reaching the filling position. In practice, however, the inlet and outlet openings are placed in 90 degree relation, to the end that each charge of syrup 30 shall be received in cooled condition directly from the syrup tank, immediately prior to its discharge from the measuring cylinder 39. To permit the charge of syrup to leave the 35 chamber 39 promptly and completely when said chamber registers with the outlet opening, a vent passage 39' in vertical alinement with discharge nipple 44 is formed in the head of the outer cylinder 30 or 31.

40 Mention has been made of the flaring or conoidal form of the openings through disks 35 and 40, the purpose of which is to facilitate the complete filling and complete discharge of the chambers. It is desirable to 45 make the filling and discharge openings smaller in diameter than the chambers 39; but it has been found in practice that if the openings be smaller than the chambers and of like diameter throughout, air will collect 50 or be pocketed in the angles where the disks and cylinders meet and will prevent the complete filling and the proper or prompt emptying of the chambers. By the construction described prompt and complete filling and 55 emptying of the chambers 39 is insured, and uniform syrup charges are assured.

60 Each inner cylinder 37 is formed or furnished with a downwardly extending stem 45 concentric with the axis of the cylinder, and 65 serving to carry a ratchet disk 46 made fast

thereto in any convenient way, a set screw 46' being shown for this purpose in Fig. 6. Ratchet disk 46 is cut away on its upper face to form a circular boss 47 concentric with the disk, and said boss is encircled by 70 an annular pawl-carrier 48 provided with a pivoted pawl 49, the free end of which is pressed toward the periphery of disk 46 by a spring 50 carried between the downwardly turned-end of a radial arm 51 of the carrier 75 48 and the pawl 49. (See Figs. 1 and 5.) The disk 46 is provided on its outer edge with a series of ratchet teeth 48', four being shown. The several teeth will in all cases be equally spaced apart, and will correspond in number with the chambers 39 in cylinder 37, with other parts constructed and arranged as here shown to advance successive chambers of the cylinder to the filling or to the discharging position by a single movement of the pawl-carrier 48 and pawl 49. Oscillating motion is transmitted to pawl-carrier 48 by a link 52 pin-jointed at one end to an ear projecting from the periphery of said carrier, and attached at its other end to a moving part of the mechanism, as later explained.

It is of course necessary to provide means for retaining in position and squarely seating the disk 40 and gasket 41, and applying adequate pressure thereto; but it is likewise desirable that these parts and the inner cylinder 37 be also readily removable from the cylinder 30 for cleaning, repair, or substitution. To attain these ends there is provided as shown in Fig. 6, an annularly flanged or cup-shaped cap 53, the flange 54 of which encircles and closely fits the exterior of cylinder 30 at its lower end, a groove 55 being formed in the inner wall of 1 said flange to receive a gasket or packing to insure a liquid-tight joint. A central opening is formed in the cap 53 for passage of axial stem 45 of cylinder 37 through it, and the cap may be applied and removed by hand and without the aid of tools.

To apply adequate pressure to cap 53 to seat it squarely upon cylinder 37, and to cause due embedding of the annular ribs of disk 40 into gasket 41, there is provided an L-shaped lever 56 which is fulcrumed at the junction of its arms in the lower end of a pendant bracket 57 secured at its upper end to cylinder 30. The horizontal arm of lever 56 is bifurcated to straddle stem 45, and both arms of the fork are formed with rounded upper faces to afford point bearings against the under face of cap 53, and to permit said cap to rock or tip thereon. Passing horizontally through a threaded hole in the upper end of the upright arm of lever 56 is a substantial screw-stem 58 provided with a milled head or other means of turning it, and bearing at its other end against the bracket 57 or the cylinder 30. By turning 1

the screw-stem to advance it toward the cylinder 30 it will, on obtaining a bearing, force outward the upright arm of lever 56, thereby elevating the lower arm thereof and applying upward pressure to cap 53 which, however, is free to rock or tip on the rounded faces of the lever arm and thus to adapt itself nicely to the cylinder 37, gasket 41, and disk 40, bringing all into close and firm bearing contact. By reversing the turning of the screw the cap can be relieved of pressure and removed. A vertical key 140 prevents turning of cap 53.

This manner of securing the cap overcomes a serious difficulty experienced with other modes of holding it in place, and insures tight joints with easy and free movement of the inner cylinder, all cramping and binding being avoided. This is highly important, particularly when the machine is to be manually operated. To permit cap 53 to seat itself readily upon the cylinder 37, the pipes or tubes 90 connecting nipple 44 with discharge nozzle 12 are made of quite flexible material such as rubber, so that no appreciable resistance to ready and perfect seating shall be offered. (See Figs. 1 and 6).

30 *The water-measuring device and distributor valve.*

In order to deliver a predetermined and unvarying quantity of carbonated water at each operation of the actuating lever, I employ a measuring cylinder 59, indicated by dotted lines in Fig. 1 and shown in sectional elevation in Fig. 13, within which is arranged a free or floating piston or diaphragm 136, the cylinder 59 being of capacity to contain the precise water charge desired, in addition to the piston. This piston 136 is moved alternately in opposite directions by the pressure of the carbonated water on first one face and then the other, as first one and then the other end of measuring cylinder 59 is connected with the carbonated-water pipe 60, which proceeds from the end of the series of cooling cylinders 26 opposite that to which supply pipe 22 is connected.

50 To effect such alternating connection of opposite ends of measuring cylinder 59 with the carbonated-water pipe, there is provided the distributor 27 heretofore mentioned, and illustrated in detail in Figs. 9 and 14. This is in fact a four-way valve, and comprises a shell or body 28 having a circular central opening 61, with which communicate at four points in 90-degree relation to one another, four pipes 60, 62, 63 and 64, as indicated in Fig. 9, 60 being the carbonated-water pipe, here shown as entering shell or body 28 at its upper side. Pipe 62 extends from the right-hand end of measuring cylinder 59 as viewed in Fig. 1, to the rear side of shell or body 28. Pipe 63 similarly extends from

the left-hand end of measuring cylinder 59 to the left-hand side of shell 28, and pipe 64 extends from the lower side of said shell to the discharge or dispensing nozzle 12. The general arrangement of the pipes is best seen 70 in Fig. 5.

Within the circular and slightly conical opening 61 of shell 28 there is arranged a closely fitting, similarly conical, rotatable plug or valve 65, formed with axial extensions to carry ratchet wheels or disks 66 (Figs. 2 and 5), by either of which the valve may be turned through the medium of one or the other of two reciprocating pawls 67, as later explained. To hold plug or valve 80 65 in its seat against the pressure of the carbonated liquid, there is provided a screw 135 passing through a threaded opening in a fixed arm or support, and bearing at its forward end against the axial extension at 85 the larger end of plug 65 (see Fig. 14). This screw 135 also serves to adjust the plug axially to take up wear, should this be necessary.

The plug 65 has four openings in its circumference, spaced 90 degrees between centers, said openings being connected in pairs as seen in Fig. 9, so that by turning the valve plug through 90 degrees, pipe 60 may be placed in communication with either pipe 62 90 or pipe 63, while pipe 64 will be placed in communication with that one of pipes 62 or 63 which is not placed in communication with pipe 60. Each quarter turn of plug 65 will hence reverse the order of the connections, and cause carbonated liquid to flow from pipe 60 through first one and then the other of pipes 62, 63 to the pipe 64, and thence to the dispensing or discharge nozzle 12. 105

In this way carbonated water is delivered to the measuring cylinder 59 at the end at which piston 136 is at the moment located, and the piston is moved to the opposite end by the pressure of the entering water, thereby forcing out at said opposite end of the measuring cylinder the previously contained charge. As a result, the entering and actuating charge which moves the piston in one direction becomes on the next operation of 115 the mechanism the charge which is delivered at the nozzle 12, the filling of the measuring cylinder through one end taking place simultaneously with the delivery of its previously received charge through the opposite end, 120 and this action takes place in reverse order on successive depressions of the actuating lever 29.

The piston 136 has a somewhat free or loose fit within the measuring cylinder 59, and in order to prevent water passing around said piston and to the outlet toward which the piston has last moved, the faces of the piston are each provided with one or more 125 annular V-shaped ribs 137. These ribs are 130

pressed firmly into the face of a gasket 138 (of which there is one at each end of said cylinder), and produce an effective seal against the passage of water around the piston and to the proximate outlet.

The actuating lever and connections.

The actuating lever 29 is seen in Figs. 1, 2, 4 and 5. It projects through the front of the casing and is preferably set to occupy normally an upwardly inclined position, as in Figs. 2 and 4. The lever is carried at its inner end by a rock-shaft 68 journaled in a framework 69 secured to and suspended from floor or plate 4, and serving to support and guide other parts presently to be noted. The rock-shaft has coiled about it a helical spring 70, one end of which is made fast to frame 69, while the other end is attached to a sector gear 71 made fast to the rock-shaft to rock or oscillate therewith, such connections being conveniently made by bending the ends of the spring laterally and forcing them into holes drilled in frame 69 and gear 71, respectively. Spring 70 serves to hold lever 29 normally in its elevated position, and to restore it and connected parts to normal position after its depression and release.

Gear 71 meshes with arid gives motion to a toothed rack 72, formed upon or secured to a cross-head or sliding block 73 which rests and slides upon the lower member of supporting frame 69, as seen in Fig. 1. Cross-head or block 73 moves in a right line toward and from the rear of the machine in response to depression and release of lever 29. It is provided with two horizontal holes 74 and 75 which are axially alined with two rods 76 and 77, the rear ends of which pass through and are guided by hangers 78, 79, and the forward ends of which enter the holes 74 and 75 of cross-head 73. Each of said rods 76, 77 carries an upstanding rod or stem 139, the upper end of which moves in a slot in an overhanging guide and prevents the rods from turning. The rear or inner ends of rods 76, 77 protrude beyond the hangers 78, 79, and each is provided in rear of its hanger with a collar 80 made fast at any desired adjustment by a set screw or other fastening. The collars serve to determine and to limit the forward movement of the rods, which is caused by springs 81, here shown of helical form, encircling said rods, and bearing at their inner ends against hangers 78, 79, and at their forward ends against adjustable blocks 82 encircling the rods, and held at proper adjustment by set screws or equivalent means.

The holes 74, 75 of cross-head 73 are of size to permit rods 76, 77 to pass freely through them, hence unless some means be provided to effect engagement of the cross-head and the rods, the cross-head may move freely back and forth without imparting

motion to the rods. Such connection is made by the coin or token required to be deposited preparatory to obtaining a charge or drink of the beverage, and as choice of syrups is offered, there must be one coin slot 70 and coin tube for each syrup, in the present case two. One such coin tube 82 is shown in Figs. 2 and 4, and each such tube extends downward at an angle from a coin slit or opening 83 in the front of the casing to a point just over one of two coin seats 84, 85 formed in cross-head 73, as best seen in Figs. 4 and 5, said seats extending through the cross-head so that the coin may rest upon and be carried over the bottom plate or member of supporting frame 69. A coin or token dropped in either coin seat 84 or 85 will bridge the hole 74 or 75, and cause the rod 76 or 77 in alinement with the coin to be pushed forward as the cross-head advances, while the other rod will remain at rest. Each rod actuates a different syrup dispenser, and each coin slot has associated with it the name or designation of the syrup which will be dispensed in response to insertion of a coin or token therein, and operation of lever 29. 91, 91 indicates two blocks fixed on the respective rods 76, 77, each carrying a roller 92, and each roller serving when its carrying rod is advanced, 95 to actuate the cup release and to cause a cup to be delivered beneath the nozzle 12.

The syrup dispensers and the distributor valve are actuated as follows:

Attached in any convenient way to the under side of floor 4 is a short bracket 86 (see Fig. 2), to which is pivoted the upper end of a pendulous lever 87 having a vertical slot 88, through which passes a stud or tap bolt 89 carried by one of the two blocks 82 secured to rods 76 and 77, respectively. To the lower end of lever 87 is jointed or pivoted one end of link 52, which as heretofore explained, gives oscillatory motion to the annular pawl-carrier 47, which imparts step-by-step rotation to ratchet disk 46 and through this to the inner syrup-measuring cylinder 37. Each of the blocks 82 carried respectively by rods 76 and 77 has pivotally connected to it one of the push-pawl 67 115 already noted, which serve to engage successively with the several teeth or arms of one of the ratchet disks 66 of the four-way valve or distributor 27, and thereby to rotate the plug 65 of said distributor a quarter 120 turn at each reciprocation of either of said rods.

The gas valve.

The gas valve 23 before referred to is seen in its proper relation to other parts of the apparatus in Figs. 2 and 8, and its details are illustrated in Figs. 10, 11 and 12.

The valve comprises two main parts, a fixed cylindrical body 93 having passages 139

94, 95 and 96 within it, extending longitudinally thereof to different distances, and each turning outward and opening at the circumference of said body; and an oscillating or 5 rocking valve proper, 97, held in close face-wise contact with that end of body 93 at which passages 94, 95 and 96 terminate. The rocking valve member 97 is of circular form, and is arranged to make close contact with 10 the end face of body 93. It is provided on its face with annular ribs 98 and 99 of V-shape in cross section, concentric with the common axis of valve member 97 and body 93, said ribs being seated in complementary 15 grooves 100 and 101 formed in the end of body 93. By this arrangement the parts are maintained in axial alignment, and a close joint is secured between the valve and body, preventing escape of gas between them and 20 thence from one passage to another.

Each passage 94, 95 and 96 is provided with a nipple 102 at its mouth at the circumference of cylindrical body 93 to receive 25 couplings 103, by which to connect the pipes 24, 13 and 25. Pipe 24 connects with the nipple of passage 96, as seen in Fig. 8 and more clearly in Fig. 10. The valve member 97 has a central opening 104 extending from its inner face partway through toward its 30 outer face, connected by a radial passage 105 with an inwardly extending branch 106, the mouth of which stands directly opposite and in register with the mouth of passage 95 when the parts are at rest or in normal 35 position. Gas will then enter by pipe 24 into passage 94, and by it pass into the axial mouth 104 to passage 105, by mouth 106 to passage 95, and thence by pipe 13 to water tank 14, the mouth of passage 96 being at 40 such time opposite a blank or solid portion of the inner face of valve member 97, and hence sealed.

If now the radial arm 97^a of valve member 97 be moved in the direction of the arrow in 45 Figs. 2 and 11, the mouth or branch 106 of the radial passage 105 of valve member 97 will be carried from the position indicated in said figures to the position indicated in Fig. 12, where it will register with the mouth 50 of passage 96, causing the gas to be cut off from water tank 14 and delivered by pipe 25 to the first carbonator tank 15. Simultaneously with this change, a vent passage 107 extending entirely through valve member 97 55 from face to face will be brought by the same movement into register with passage 95, which being at all times connected with the water tank 14 by pipe 13, will vent said tank.

60 The cylindrical body 93 of gas valve 23 is here shown extending within the annular flange of a circular head 108, carried by a bracket 109 projecting from a substantial supporting plate 110, having a horizontal foot or base 111 bolted or otherwise secured

to the floor 5 of the machine casing. To prevent turning of body 93, a hole is drilled in its end to receive a pin 112 projecting from the head 108 as seen in Fig. 10. To maintain close and sealing contact between 70 the valve member 97 and the cylindrical body 93, screws 113 and 114 may be provided, either or both being adjusted to compensate for wear, or to permit separation of the parts for inspection, cleaning, etc. Either 75 screw alone may be used but two are shown and may be deemed preferable, since proper adjustment can thereby be made without disturbing or throwing out of position pipes 13, 24 and 25, or the actuating arm 97^a of valve 80 member 97.

To cause the radial arm 97^a of valve member 97 to be swung in the direction indicated by arrow in Figs. 2 and 11, and to return automatically but at carefully predetermined 85 speed or timing in order to afford time for proper functioning of the beverage-dispensing devices, there is provided the mechanism illustrated in Figs. 2 and 3. This consists of a lever 115 fulcrumed at a point between 90 its extremities on an arm of the supporting plate 110, said lever being bifurcated at its upper end and slotted at its lower end to permit play of a connecting pin or stud carried by the radial arm 97^a of valve member 97. The two arms or branches of the upper end of lever 115 stand directly in the paths of the two rods 76, 77, as seen in Figs. 2, 5 and 8; hence the lever 115 is forced backward whenever either rod is advanced or 95 moved inward, and the lower end of said lever swinging in the reverse direction, carries with it the radial arm 97^a and thereby rocks the valve member 97 in the direction indicated by arrow. To return the lever 100 115 and valve member 97 to normal position, said lever is provided with a rod or arm 116 carrying at its free end a weight 117 tending always to swing lever 115 about its fulcrum or pivot, and to hold its upper arms 110 against rods 76, 77, or whichever one may be for the moment advanced.

To govern the speed or timing of the movement of the parts just described, I employ a pneumatic check or dashpot, comprising a 115 hollow shell or cylinder 118 open at one end and closed at the other except for a vent presently described; and a piston 119 movable within said cylinder and connected by a bar or pitman 120 with the stud or pin which connects lever 115 and valve arm 97^a (see Figs. 2 and 8). Thus arranged, the piston will be forced into cylinder 118 as arm 97^a swings in the direction of the arrow, Figs. 120 2 and 11, but with little or no resistance from the contained air (owing to an outwardly-opening vent valve 121 in the head of cylinder 118, supplemented by a second and smaller vent 122, controlled and regulated by a needle valve 123 (see Fig. 3). On 130

the reverse movement, however, the piston and connected parts are retarded, owing to the seating of valve 121 and to the small capacity of vent 122, which can be reduced 5 to a minimum through adjustment of the needle valve.

Full-throw device.

In Fig. 4 I have shown means to compel 10 a full throw of actuating lever 29 if it be carried far enough to deliver a cup or a charge therefor, thus preventing a second operation without return of the lever to normal position and introduction of another 15 coin or token. This comprises a disk 124 made fast to rock-shaft 68 which constitutes the fulcrum of actuating lever 29, said disk being provided with peripheral notches 125 adapted to receive the end of either of two 20 pawls 126, 127 carried by a rocking pawl-carrier 128 pivotally supported on the frame 69. The pawl-carrier is rocked on its pivot to cause first one and then the other pawl to enter the notches of disk 124, by horns or 25 spurs 129, 130 projecting from the periphery of disk 124, and is held in either of its two positions by the co-action of a V-shaped projection 131 on the pawl-carrier, and a V-shaped rib 132 of a spring 133 made fast 30 at one end to frame 69.

When lever 29 returns to its normal position after operation, as indicated in Fig. 4, horn 130 bears against pawl 127 and carries projection 131 to the right of rib 132, whereupon 35 spring 133 exerts its pressure to maintain the pawl-carrier 128 in such adjustment, though allowing sufficient play thereof to permit the pawl to ride from one notch to another as disk 124 is rotated, and thus 40 to prevent retrograde movement of lever 29. As the lever nears completion of its full actuating movement, and just after the beverage charge is delivered, horn 129 rides over pawl 126 and rocks pawl-carrier 128 45 far enough to reverse the positions of projection 131 and rib 132, causing spring 133 to act to press pawl 126 into engaging relation with notches 125, and to withdraw pawl 127 and maintain it out of such relation.

Fig. 4 also shows a plate 134 carried by cross-head 73, and serving when the cross-head moves forward with a coin in pocket 84, to prevent a second coin escaping from the coin tube 82 until the cross-head again 50 moves outward to its normal position.

It is manifest that by providing the upper end of lever 115 with a greater number of arms, it may be operated by a greater number of rods such as 76 and 77, associated 55 with like dispensing devices.

In practice it is preferred to combine in the one structure the several devices above set forth and illustrated, all of which co-operate and are necessary to the attainment 60 of a given end,—the preparation and de-

livery into a suitable receptacle of a carbonated and flavored beverage. It is obvious, however, that omissions may be made if a cheaper and simpler machine be desired; thus the cup-dispensing mechanism, 70 the coin-control feature, the individual carbonator within the machine, or the syrup-measuring and delivering devices may, one or more, be omitted, leaving the retained mechanisms or devices to perform their 75 several functions, but ordinarily the complete combination will be employed. Where a group or battery of the dispensing machines is employed, a carbonator common to several or all of the machines of the group 80 may be employed, and this may be external to the casings of said machines or any of them. It may also in some cases be desirable to omit the carbonator and use water which has been previously carbonated, which 85 in many cases is delivered in tanks or containers from a central charging station.

The drawings show the machine provided with a manual actuating lever, but it is obvious that where numerous sales are to be 90 made, particularly where a considerable number of machines are grouped, it may be desirable to actuate the mechanism by power after the proper coin or token is deposited. It is hence to be understood that 95 any suitable form or type of motor may be employed, suitable connection being made between the same and lever 29, which in that event may or may not extend beyond the casing of the machine.

The usual sanitary safeguards as to material or lining of containers, pipes and passages throughout the apparatus, to prevent chemical or other action injurious to the beverage delivered, are of course contemplated. 105

No claim is made herein to coin actuation or to coin control apparatus per se, nor broadly to the use of a coin or token to connect operative parts, such being old and well-known.

The mechanism herein illustrated for preventing retrograde movement of the main lever 29 after it has been moved slightly in actuating direction, is not specifically claimed by me. Such mechanism merely 115 illustrates one of a variety of known devices which may be employed for the purpose. So far as I am aware no one has heretofore equipped a vending or dispensing apparatus with means for preventing premature retrograde movement of a main actuating lever. Such premature return movement should be prevented lest only a partial charge be delivered, and also to guard 120 against a second actuation of said lever and delivery of a charge without performing prior to such second actuation, a prescribed act or condition of use.

No claim is made herein to the syrup-measuring devices per se, the same having 130

been divided out of this application and embodied in divisional application Serial No. 223,956, filed October 4, 1927, pursuant to official requirement.

5 Having described my invention, I claim:

1. In a liquid-dispensing machine, a casing comprising upright corner posts; horizontal members between said posts and forming supports for floors; and a floor or 10 plate resting upon said connecting members and carrying the principal operative mechanism, said floor being readily removable from and replaceable in the casing, whereby the mechanism can be quickly removed, inspected in assembled form, repaired, and replaced.

2. In combination with vertical angle-iron posts and intermediate horizontal floor supports of a vending machine casing or cabinet, one wing of each of two of said posts on one side of the casing having notches above the floor supports; a floor or plate slideable through said notches to and from its seat on said supports, whereby said floor may be 20 quickly removed with the mechanism assembled on it; for inspection or repair of said mechanism, and be replaced after such inspection or repair.

3. In a liquid-dispensing apparatus, the 30 combination of a water-tank; a carbonator for the water; a gas valve for delivering gas alternately to the water-tank and to the carbonator; a syrup tank; a water-measuring device; a syrup-measuring device; a cup container; means for actuating a device for delivering cups from said container one at a time; means for actuating the gas valve, the measuring devices, and the cup-delivery mechanism; a main actuating lever; and connections between said lever and the measuring devices, cup-delivery device, gas valve, and actuating lever, whereby all are caused to function when the lever is actuated.

4. In a liquid-dispensing apparatus, the 45 combination of a water-tank; a carbonator for the water; a valve for delivering gas alternately to the water-tank and to the carbonator; a syrup tank; a water-measuring device; a syrup-measuring device; means for actuating the measuring devices and the gas 50 valve; a main actuating lever; and intermediate connecting means between said measuring devices, gas valve, and said actuating lever, whereby all are caused to function when the lever is actuated.

5. In a liquid-dispensing apparatus, the 60 combination of a water-tank; a source of gas; a carbonator for the water; a gas valve for directing gas alternately to the water-tank and to the carbonator; a water-measuring device; a syrup tank; a syrup-measuring device; a cup container; means for actuating a device for delivering cups one at a time from the container; means for individually actuating the gas valve, the measuring

devices, and the cup delivery device; a main actuating lever; and connections between the separate actuating devices and the main actuating lever, whereby all of said individual actuating devices are caused to function in proper time and sequence in response to actuation of said lever.

6. In a liquid-dispensing apparatus, the combination of a water-tank; a gas container; a carbonator for the water; a gas valve for directing gas alternately to the water tank and to the carbonator; a water-measuring device; a syrup tank; a syrup-measuring device; a cup container; means for actuating a device for delivering cups 70 one at a time from the container; means for individually actuating the gas valve, the measuring devices, and the cup delivery device; a main actuating lever; a cross head movable by said lever and provided with an opening to receive a rod; and a rod for transmitting motion from the cross head to the individual actuating devices, said rod being alined with and having its proximate end normally separated a slight distance 80 from, the mouth of the opening in the cross head.

7. In a liquid dispensing apparatus, the combination of a water-tank; a carbonator for the water; a valve for delivering gas alternately to the water-tank and to the carbonator; a syrup tank; a water-measuring device; a syrup-measuring device; means for actuating the measuring devices and the gas valve; a main actuating lever; means for preventing retrograde movement of said actuating lever after its actuating movement is begun and before completion of said movement; and intermediate connecting means between said measuring devices, gas valve 95 and actuating lever, whereby all are caused to function when the lever is actuated.

8. An apparatus for dispensing beverages, comprising in combination with suitable dispensing devices, a gas valve consisting of a body 93 having passages 94, 95 and 96, and a valve member 97 having a passage 105 with mouths 104 and 106 opening toward the body 93 and having a vent opening 107 entirely through it, one of the parts 93, 97 being movable relatively to the other to bring the central gas passage 94 alternately into communication with passage 95 leading to a water-tank and with passage 96 leading to a carbonator, and to vent passage 95 to the atmosphere when communication is established between passages 94 and 96; a carbonated-water supply pipe; a water-measuring device comprising a cylinder and a floating piston therein; a delivery nozzle;

and a distributor consisting of a valve body or shell and four pipes entering said shell in 90 degree relation, one of said pipes communicating with a source of carbonated liquid, two others communicating respectively 125

with opposite ends of the water-measuring cylinder, and the fourth pipe communicating with the delivery nozzle.

9. In an apparatus for dispensing a carbonated beverage, the combination of a main water-tank; a carbonator communicating with said tank; a source of carbonic acid gas; a gas valve for alternately venting the water-tank to the atmosphere and directing the gas to the carbonator, and sealing the tank to the atmosphere and directing the gas to the water-tank; and means for retarding the movement of the gas valve in one direction.
10. In an apparatus for vending a carbonated beverage, the combination of a main water-tank; a carbonator communicating therewith; a source of carbonic acid gas; a valve for alternately venting the water-tank to the atmosphere to permit inflow of water and simultaneously delivering gas to the carbonator, and then sealing the water-tank to the atmosphere and delivering the gas to said tank; a piston connected and movable with said valve; a main vent for the cylinder of said piston; an outwardly-opening valve for said vent; a second vent for the cylinder of the dash-pot; and a valve for controlling the capacity of said second vent, whereby a relatively quick movement of the gas valve in one direction and a relatively slow movement thereof in the reverse direction may be secured.

11. A beverage-dispensing apparatus, comprising a carbonating-gas container; a water-container; means for delivering gas from the gas container to the water; a beverage delivery nozzle; a cup container; means for actuating a device for delivering a cup from the cup container to a position beneath the nozzle; means for delivering measured quantities of the carbonated water to the nozzle; a syrup container; means for delivering measured quantities of syrup from the syrup-container to the nozzle; a main actuating lever; and means intermediate the nozzle and the actuating lever, whereby upon actuation of the lever a cup is

delivered to a point beneath the nozzle, gas is delivered to the water in the water container, a charge of carbonated water and a charge of syrup are delivered to the delivery nozzle, and the carbonated water and syrup are delivered from the nozzle to, and are mingled in, the cup.

12. A beverage-dispensing apparatus, comprising a carbonating-gas container; a water container; means for delivering gas from the gas container to the water; a beverage delivery nozzle; a cup container; means for actuating a device for delivering a cup from the cup container to a position beneath the nozzle; means for delivering measured quantities of the carbonated water to the nozzle; a syrup container; means for delivering measured quantities of syrup from the syrup-container to the nozzle; a main actuating lever; and means intermediate the nozzle and the actuating lever, whereby upon actuation of the lever, a cup is delivered to a point beneath the nozzle, gas is delivered to the water in the water container, a charge of carbonated water and a charge of syrup are delivered to the delivery nozzle, and the carbonated water and syrup are delivered from the nozzle to, and are mingled in, the cup.

13. In a carbonated-liquid dispensing machine, the combination of a water supply; a gas valve for delivering gas to said water; a lever for actuating said valve, provided with a plurality of arms; a plurality of syrup containers, each provided with a device for delivering a measured charge of syrup; a plurality of rods, each connected with one or another of the syrup-delivery devices and each in alinement with one or another arm of the gas lever; and a main actuating lever adapted to be connected with and to actuate any selected one of said rods at will, and thus to actuate simultaneously any selected syrup-delivery device and the gas valve.

In testimony whereof I have signed my name to this specification.

JOHN L. PATTERSON.
